U.S. Appl. No. 29/703,774, filed Aug. 29, 2019, Hangartner et al.

Primary Examiner — Philip S Hyder

(74) Attorney, Agent, or Firm — Reinhart Boerner Van Deuren s.c.

(57) **CLAIM**

We claim the ornamental design for a knife, as shown and described.

DESCRIPTION

FIG. 1 is a top, right perspective view of a knife, embodying the new design.

FIG. 2 is a front view of the knife of FIG. 1.

FIG. 3 is a rear view of the knife of FIG. 1.

FIG. 4 is a right view of the knife of FIG. 1.

FIG. 5 is a left view of the knife of FIG. 1.

FIG. 6 is a top view of the knife of FIG. 1.

FIG. 7 is a bottom view of the knife of FIG. 1.

FIG. 8 is a top, right perspective view of the knife of FIGS. 1 through 7, depicted using a wire frame drawing technique.

FIG. 9 is a front view of the knife of FIG. 8.

FIG. 10 is a rear view of the knife of FIG. 8.

FIG. 11 is a right view of the knife of FIG. 8.

FIG. 12 is a left view of the knife of FIG. 8.

FIG. 13 is a top view of the knife of FIG. 8; and,

FIG. 14 is a bottom view of the knife of FIG. 8.

The ornamental design which is claimed is shown in solid lines in the drawings.

1 Claim, 12 Drawing Sheets
